UNITED STATES PATENT OFFICE.

WORTHINGTON G. OGBORN, OF SALT LAKE CITY, UTAH.

SEPARATE COLLAR FOR SWEATERS.

1,199,813.

Specification of Letters Patent.

Patented Oct. 3, 1916.

Application filed March 27, 1916. Serial No. 87,023.

To all whom it may concern:

Be it known that I, WORTHINGTON G. OGBORN, a citizen of the United States, residing at Salt Lake City, in the county of 5 Salt Lake and State of Utah, have invented certain new and useful Improvements in Separate Collars for Sweaters; and I do declare the following to be a full, clear, and exact description of the invention, such as 10 will enable others skilled in the art to which it appertains to make and use the same.

This invention relates to new and useful improvements in collars, and more particularly to a separate collar adapted to be applied to a certain type of sweaters which have an open front, and the object of the invention is to form a continuous high collar for the same when applied thereto.

A further object of this invention is to 20 provide a collar of this character which is adapted to be held upon the neck of the sweater by tension, and which is also adapted to be folded upon itself.

A still further object of the invention is 25 to provide a device of this character which will be simple and durable in construction, inexpensive to manufacture and one which will be very efficient in operation.

With these and other objects in view, the 30 invention resides in certain novel features of construction, combination and arrangement of parts which will be hereinafter more particularly described and claimed, and shown in the drawings wherein:

35 Figure 1 is a front view of the type of sweater to which my improved collar is applicable; Fig. 2 is a view similar to Fig. 1 showing the collar applied to the sweater; Fig. 3 is a detail view of the neck of the 40 sweater showing the collar applied thereto, the front portion of the collar being broken away and shown in section; and, Fig. 4 is a similar view to Fig. 3 showing the collar folded.

45 In describing my invention I shall refer to the drawings in which similar reference characters designate corresponding parts throughout the several views and in which the numeral 1 designates an ordinary type 50 of sweater having an open buttoned front as shown at 2 either extending its entire length or only part way from the top. This sweater is provided with a short length collar as shown at 3 which is of the ordinary style used in sweaters of this character.

55 My invention comprises an endless tubular

knitted strip 4 which is adapted to form two sections 5 and 6 which have their upper and lower edges 7 and 8 connected. This collar is provided with transversely extending ribs 9 which extend between the upper and lower edges of the same.

The collar 4 is so knitted or made that the same is provided with a plurality of circumferentially extending tension zones 65 which are progressively decreased from a tight tension zone 10 intermediate said ribs to a loose tension zone at the upper and lower edges 7 and 8 of the collar. By this construction, and owing to the fact that the 70 collar is so formed that it is slightly smaller at its lower edge than the neck 3 of the sweater to which it is applied, it will be obvious that when the same is placed thereon, a sufficient tension will be created by the 75 tension zone at its lower edge to hold the same securely engaged with the said collar of the sweater around the wearer's neck, while the tight tension zone 10 intermediate the upper and lower edges of the collar will 80 tend to hold the same firmly in contact with the neck of the wearer. By this means, the collar will be firmly and securely held in engagement without the necessity of employing any additional fastening means for connecting the same to the sweater. This collar is also adapted to be folded at the zone of 85 tight tension 10 which is the point intermediate its upper and lower edges, in a manner clearly shown in Fig. 4 of the drawings, 90 whereby the line of fold will form the upper edge of the collar. This allows the full neck to be turned down to one-half its original height, when desired.

The collar owing to the fact that it is 95 formed from an endless knitted strip is adapted to stretch, so that it may be easily brought over the wearer's head without disarranging the hair. This collar provides a continuous full height collar for an open front sweater, and when it is not desired to use the same, it may be easily removed, and the sweater turned down. By the use of a continuous separate collar of this character, it will be obvious that an open front sweater 100 is adapted for use in extremely cold weather, and as has been above described, this collar may be easily placed thereon, and the same will afford a protection for the neck and lower part of the face as is common to the 105 type of sweaters which have a continuous collar formed thereon. The continuous col-

lar type of sweater, however, is inconvenient owing to the fact that the high full collar cannot be removed therefrom, and it is also very difficult to put on and take off. By the 5 use of the type of continuous collar embodied in this invention, an open front sweater may be adapted to be applied to all the uses of a continuous collar sweater with no open front, and all disadvantages of the 10 same are overcome.

From the foregoing description of the construction and operation of this invention, the use of the same will be readily understood and it will be seen that I have provided a 15 very simple construction for carrying out the objects of the invention.

I claim as my invention:

A separate collar for short neck sweaters comprising a tubular endless knitted strip 20 adapted to surround the neck of the wearer, said strip having ribs extending transversely from the edges of the same, a medial tight tension zone adapted to snugly and elasti-

cally engage the neck of the wearer above the short neck of the sweater, circumferentially extending progressively decreasing zones of tension on said collar from the medial zone terminating in loose tension zones adjacent its top and bottom edges and adapted to respectively engage the lower 30 portion of the face of the wearer, and the short collar of said sweater, and said collar adapted to be folded at the medial zone of tension whereby the line of fold forms its upper edge and the folded upper portion 35 will additionally secure the engagement between the lower portion and the short collar of the sweater.

In testimony whereof I have hereunto set my hand in presence of two subscribing witnesses.

WORTHINGTON G. OGBORN.
